(57) **CLAIM**

The ornamental design for a digital stylus with transparent nib, as shown and described.

DESCRIPTION

FIG. 1 is a front-right-top perspective view of a digital stylus with transparent nib according to our new design; FIG. 2 is a front-left-bottom perspective view thereof; FIG. 3 is a front elevational view thereof, the digital stylus with nib being radially symmetrical about a central axis; FIG. 4 is a left side elevational view thereof; FIG. 5 is a right side elevational view thereof; FIG. 6 is a partial front-right-top perspective view thereof as indicated in FIG. 1; FIG. 7 is a partial front-left-bottom perspective view thereof as indicated in FIG. 2; and, FIG. 8 is a partial front elevational view thereof as indicated in FIG. 3.

The dashed broken lines in the drawings show portions of the digital stylus with transparent nib that form no part of the claimed design. The dot-dot-dash broken lines in the drawings indicate from where the partial views are taken and form no part of the claimed design.
